CLAIM

The ornamental design for an insert for an arthropod trapping device, as shown and described.

DESCRIPTION

FIG. 1 is a front, right-side isometric view of a first embodiment of an insert for an arthropod trapping device;

FIG. 2 is a rear, left-side isometric view of the insert for an arthropod trapping device of FIG. 1;
 FIG. 3 is a front view of the insert for an arthropod trapping device of FIG. 1;
 FIG. 4 is a right side view of the insert for an arthropod trapping device of FIG. 1;
 FIG. 5 is a rear view of the insert for an arthropod trapping device of FIG. 1;
 FIG. 6 is a left side view of the insert for an arthropod trapping device of FIG. 1;
 FIG. 7 is a top view of the insert for an arthropod trapping device of FIG. 1;
 FIG. 8 is a bottom view of the insert for an arthropod trapping device of FIG. 1;
 FIG. 9 is a front, right-side isometric view of a second embodiment of an insert for an arthropod trapping device;
 FIG. 10 is a rear, left-side isometric view of the insert for an arthropod trapping device of FIG. 9;
 FIG. 11 is a front view of the insert for an arthropod trapping device of FIG. 9;
 FIG. 12 is a right side view of the insert for an arthropod trapping device of FIG. 9;
 FIG. 13 is a rear view of the insert for an arthropod trapping device of FIG. 9;
 FIG. 14 is a left side view of the insert for an arthropod trapping device of FIG. 9;
 FIG. 15 is a top view of the insert for an arthropod trapping device of FIG. 9;
 FIG. 16 is a bottom view of the insert for an arthropod trapping device of FIG. 9;
 FIG. 17 is a front, right-side isometric view of a third embodiment of an insert for an arthropod trapping device;
 FIG. 18 is a rear, left-side isometric view of the insert for an arthropod trapping device of FIG. 17;
 FIG. 19 is a front view of the insert for an arthropod trapping device of FIG. 17;
 FIG. 20 is a right side view of the insert for an arthropod trapping device of FIG. 17;
 FIG. 21 is a rear view of the insert for an arthropod trapping device of FIG. 17;
 FIG. 22 is a left side view of the insert for an arthropod trapping device of FIG. 17; FIG. 23 is a top view of the insert for an arthropod trapping device of FIG. 17; and,
 FIG. 24 is a bottom view of the insert for an arthropod trapping device of FIG. 17.
 The broken lines illustrate structure or features that form no part of the claimed design.
 The dot-dash broken lines define the bounds of the claimed design and form no part thereof. The drawings include shadows and reflections that indicate contour, not surface ornamentation.
 The gray shading illustrates color contrast, not surface ornamentation or a particular color.
